UNITED STATES PATENT OFFICE

CHRISTIAN DANTSIZEN, OF SCHENECTADY, NEW YORK, ASSIGNOR TO GENERAL ELECTRIC COMPANY, A CORPORATION OF NEW YORK

REFRIGERANT

No Drawing.

Application filed May 21, 1929. Serial No. 364,942.

My invention relates to a new and improved refrigerant.

I have discovered that methyl formate, (H.COOC₂H₅), as a refrigerant is superior in some refrigeration systems to the common refrigerants now in use. It possesses characteristics and properties which render it very valuable for use as a refrigerating medium. This organic substance may be used 10 as a refrigerant without admixture with any other substance.

Methyl formate has a normal boiling point of about 33° C. Its vapor pressure at normal temperatures is thus low enough so that it 15 can be transported in cork stoppered, glass bottles, and yet high enough at, say, -10° C., to permit its use in a refrigerating machine. This property makes it admirably suited for use with certain types of low pressure 20 refrigerators, such as the rotary compressor types. It is heavier than, and practically not miscible with the lubricating oils ordinarily used in refrigerating machines; that is, it is not miscible in all proportions 25 with lubricating oils. Both of these properties are highly desirable in refrigeration. Since it is substantially not miscible with oil, there is no danger of materially thinning the lubricating oils, as is the case with organic 30 halides which are used as refrigerants. This is a decided advantage. It is non-corrosive and, hence, does not attack the metal parts with which it comes in contact. It is relatively non-poisonous and therefore suited for 35 use in domestic refrigerating machines.

In use, methyl formate may be employed in a system of refrigeration, as in the compressor type, passing through the cycle of first being compressed by the compressor, 40 then to a condenser, from there to an expansion chamber, or evaporator, and finally returning to the compressor to complete the cycle.

Since methyl formate has a low vapor pressure 45 at high temperatures and is relatively non-poisonous, it is well adapted for use in heating systems employing the refrigeration cycle. In such a system the heat may be absorbed from outside of the building by evaporation of the methyl formate at low pressure 50

sure and temperature, and liberated by being compressed and condensed in radiators within the building to be heated.

What I claim as new and desire to secure by Letters Patent of the United States, is:

A refrigerating system comprising a compressor, said system having oil therein for lubricating the parts of said compressor, a condenser, an evaporator, and a refrigerant circulated through the system by said compressor and coming in contact with said lubricating oil, said refrigerant consisting of methyl formate without admixture with ether or any other substance which would cause it to become miscible to any substantial extent with said lubricating oil.

In witness whereof, I have hereunto set my hand this 20th day of May, 1929.

CHRISTIAN DANTSIZEN.
